UNITED STATES PATENT OFFICE

GEORGE R. KRABER, OF NEWTONVILLE, MASSACHUSETTS, ASSIGNOR TO WARREN
TELECHRON COMPANY, A CORPORATION OF MAINE

DESIGN FOR A CLOCK CASE

Application filed October 26, 1931. Serial No. 41,530. Term of patent 14 years.

To all whom it may concern:

Be it known that I, GEORGE R. KRABER, a citizen of the United States, residing at 516 Watertown Street, Newtonville, county of Middlesex, State of Massachusetts, have invented a new, original, and ornamental Design for a Clock Case, of which the following is a specification, reference being had to the accompanying drawings forming a part

thereof. Fig. 1 of the drawings is a front view of a clock case, and Fig. 2 a side view thereof, showing my new design.

I claim:

The ornamental design for a clock case as shown.

In witness whereof, I have hereunto set my hand this 2d day of September, 1931.

GEORGE R. KRABER.
